COLLAPSIBLE TUBE, CONTAINER, AND
RECEPTACLE

Robert Williamson Storrs, Jr., Richmond, Va.

Application August 10, 1934, Serial No. 739,291

1 Claim. (Cl. 221—60)

This invention relates to collapsible tubes, containers and receptacles, and more particularly to tubes provided with receptacles provided with detachable caps. At the present time it is cus-

5 type of collapsible receptacle is illustrated although, as is well known, any material or type of receptacle may be employed that is within the scope of this invention.

5 tomary in the manufacture of collapsible tubes, receptacles and the like, to accompany such devices with caps or stopping members. For instance, in a collapsible tube of ordinary tooth paste a screw cap generally accompanies same.

10 A cap or lid 4 is provided with bearing or claw-like member 5 adapted to be disposed in a journal or socket 6; said socket and bearing engage each other and thereby provide a pivotal point about which the cap may be actuated in circumferential fashion. The cap may be countersunk inwardly to permit the disposition of a washer 7 adapted to securely stop the outlet and prevent air contacting the material as well as stop any leakage. 15

10 One of the apparent difficulties in the usual cap or stopper is that when the operative removes the cap from the tube or container, there is danger of same being misplaced or falling into obscure places subjecting the cap to being lost.

15 Also, certain paste and liquids housed in receptacles are subjected to hardening when exposed to the air over a period of time, and the inadvertent failure of the operative to replace cap on the container, possibly due to laying the former 20 one place and the latter another, causes such materials to harden.

Upon the surface of the cap and/or bearing is a slot or groove 8 adapted to register with and provide a path for a spring or resilient member 9, one end of which is housed or secured in housing members 10 while the other free end is disposed in the groove and exerts a force when in 20 closed position that keeps the cap thus, and also a force against the cap that keeps the latter in open position, when so placed. 15

20 In view of the foregoing, one of the objects of this invention is the provision of a receptacle having a cap engaging the outlet of a container and in operative relation thereto in pivotal fashion.

25 Fig. 6 is a modification in which a container 20 is provided with a cap 21 secured to said container, in pivotal fashion by a hinge 24', and having a detent 23 in said cap adapted to engage a nipple 24. Upon pressure of said cap against the outlet 25 it will be forced over the nipple and snapped securely to the container. By exerting pressure upwardly in close proximity to the fastener, or pressing handle 26 downwardly, the cap may be flipped open with one hand. It is obvious from the foregoing that both the inventions described herein may be manipulated 30 and held by one hand at the same time. 35

25 Another object of this invention is the provision of a container or receptacle having a cap or lid contacting at all times said container and in operative relation with the orifice or outlet thereof.

30 Having described this invention what is claimed is:

35 A further object of this invention is the provision of a receptacle having a cap that an operative may manipulate with one hand while holding said receptacle.

40 Other objects and features will more fully appear from the following description and accompanying drawing in which: Fig. 1 is a side view; Fig. 2, a rear view; Fig. 3, a side view showing cap in open position; Fig. 4, a partial sectional view; Fig. 5, a top plan view and Fig. 6, a modification.

In a device of the character described consisting of a container, a cap pivotally connected to 40 said container; a groove on said cap, and a resilient member engaging said groove and secured to said container to cause said cap to remain either in open or closed position as the case may be. 45

45 Referring to the drawing, a container 1 may be provided with a neck 2 forming an outlet or orifice 3 for the distribution of any material lodged therein. In the present illustration the usual
